UNITED STATES PATENT OFFICE.

AMOS DURANT AND HENRY GRISSIRN, OF STOCKTON, CALIFORNIA.

IMPROVED WASHING-MACHINE.

Specification forming part of Letters Patent No. 56,911, dated August 7, 1866.

To all whom it may concern:

Be it known that we, AMOS DURANT and HENRY GRISSIRN, of the city of Stockton, county of San Joaquin, and State of California, have invented a new, useful, and Improved Washing-Machine; and we do hereby declare that the following is a full and exact description of the construction and operation of the same, reference being had to the annexed drawings and the letters of reference marked thereon.

Figure 1 is a perspective view. Fig. 2 is a longitudinal section, and Fig. 3 is an end elevation.

A A are standards firmly fixed on each side of a box with a bottom forming the segment of a circle. B B are arms fixed at right angles to the standards. C C are levers on the outside of standards and box, working on the centers 1 1. D D are two other levers, to which is attached a plunger E, working in the box and suspended from centers 2 2. F F are arms attached to the lower end of levers C and to the suspension-bars G G, which are hung from the extremity of the arms B and connected by a bar, H. I is a rod passing through the upper end of levers C and D, connecting them together.

In working the machine, the clothes, with water, &c., having been placed in the box on each side of the plunger, the bar H is moved backward and forward with a reciprocating motion by hand or other power. This motion is communicated by the arms F to the levers C, working on their centers or fulcrums at 1, and these levers being connected with the levers D by the rod I, and working on centers or fulcrums 2, and being attached to the plunger E, carry it backward and forward in the box and press the clothes at each stroke against a set of cleats at each end of the box. The plunger has, also, similar alternate cleats.

We do not claim the use of the box, plunger, or cleats as our invention; but

We claim—

The application and combination of the levers C C and D D, working from different centers, and connected with the plunger E, and worked by reciprocating motion, as herein set forth.

AMOS DURANT.
HENRY GRISSIRN.
